UNITED STATES PATENT OFFICE.

JOHN WESLEY BECK, OF BELLEVUE, TEXAS, ASSIGNOR OF ONE-HALF TO NOLAN T. GAINES, OF BELLEVUE, TEXAS.

AUTOMATIC ENGINE-STARTER.

1,161,827.

Specification of Letters Patent. Patented Nov. 30, 1915.

Application filed August 27, 1915. Serial No. 47,660.

To all whom it may concern:

Be it known that I, JOHN W. BECK, a citizen of the United States, residing at Bellevue, in the county of Clay and State 5 of Texas, have invented a new and useful Automatic Engine-STARTER, of which the following is a specification.

The present invention appertains to engine starters, and aims to provide a novel and 10 improved automatic spring-actuated starter for internal combustion engines.

It is the object of the invention to provide a mechanism of the nature indicated applicable to the crank shaft of the engine, or to 15 any other shaft which is operatively connected to the crank shaft, and so constructed, that when the engine is running, the spring of the mechanism will be wound up, and when the spring is wound up sufficiently, it will be disconnected from the shaft, but will be held against unwinding, so that when the operating lever or member 20 is moved properly at a subsequent time, the spring may again be connected to the shaft, and this time to forcibly rotate the shaft to 25 start the engine.

It is the object of the invention to provide an automatic spring-actuated starter of the nature indicated, which is comparatively 30 simple and inexpensive in construction, which may be applied to various shafts at various points of their lengths, which will be thoroughly practical and efficient in operation, and which embodies a minimum 35 amount of parts.

With the foregoing and other objects in view which will appear as the description proceeds, the invention resides in the combination and arrangement of parts and in the 40 details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a side elevation of the improved starter illustrating the same in idle 50 position with the spring wound up. Fig. 2 is a longitudinal section of the mechanism illustrating the spring wound up and connected to the shaft for actuating the same. Figs. 3 and 4 are cross sectional views taken 55 on the lines 3-3 and 4-4, respectively, of

Fig. 1. Figs. 5 and 6 are enlarged sectional details taken on the lines 5-5 and 6-6, respectively, of Fig. 1.

In carrying out the invention, there is provided a pair of standards or pedestals 1 and 2 attached to the frame F, which may be the frame or chassis of an automobile, or any other supporting structure associated with the engine which is to be started. The present mechanism is adapted especially for 60 use upon automobiles, although it may be employed for other purposes as well.

The numeral 3 designates a portion of the crank shaft of the engine (not shown), although it may be taken to represent any 70 shaft which is operatively connected to the engine, this shaft 3 being journaled through the pedestals 1 and 2. A gear wheel 4 is keyed or secured upon the shaft 3 adjacent the pedestal 1, and is provided with a clutch hub 5, and a sleeve or tubular shaft 6 is mounted upon the shaft 3 for sliding and rotatory movements. One end of the sleeve 6 is provided with a clutch portion 7 co-operating with the clutch hub 5 of the gear 75 wheel 4, and the other end of the sleeve 6 is also provided with a clutch portion 8 co-operating with the clutch portion 9 of a second sleeve 10 mounted slidably upon the shaft 3. The sleeve 10 is slidable through a standard 80 11 attached to the frame F, and is provided with longitudinal slots 12 receiving pins 13 engaged to the standard 11, whereby the sleeve 10 is prevented from rotating and is limited in its longitudinal movement. A

coiled wire spring 14 is disposed upon the shaft 3 between the sleeve or clutch member 10 and a collar 15 disposed upon said shaft and seating against the pedestal 2, whereby the sleeve 10 is yieldably moved toward the 95 sleeve 6 under the influence of the spring 14. The sleeve 6 extends loosely through a standard 16 secured to the frame F adjacent the pedestal 1, and a collar 17 is secured upon the sleeve 6 adjacent the standard 16. A leaf spring 18 is secured to the standard 16 and bears against the collar 17

for yieldably moving the sleeve 6 away from the gear wheel 4 and toward the sleeve 10. It is to be understood that the springs 14 and 18 need not be of the particular type illustrated, since any spring means may be employed for pressing the sleeves 10 and 6 toward one another yieldably. The spring 18 normally moves the sleeve 6 into engage- 100 105 110

ment with the sleeve 10 and away from the clutch hub 5 of the gear wheel 4, as seen in Fig. 1.

A spiral spring 19 has its inner end secured to the sleeve 6 adjacent the standard 16 at that side of the standard opposite the spring 18 and gear wheel 4, and the outer end of the main spring 19 is connected to an outstanding pin 20 carried by the standard 16, or to any other convenient point.

A pair of arms 21 are pivotally engaged to an outstanding pin 22 carried by the standard 16 adjacent the pin 20, and the arms 21 are provided at their free ends with arcuate jaws 23 straddling the coiled portion of the spiral main spring 19, as clearly seen in Fig. 4. The arms 21 are connected by a flexible element 24, in order that when the spring 19 is unwound, it will separate the jaws 23 and thereby tend to straighten out the cord or flexible element 24.

A relatively large internal gear wheel 25 is keyed or secured upon the sleeve 6 adjacent that end of the sleeve having the clutch portion 8, the wheel 25 having internal teeth 25^a which are relatively long. This gear wheel 25 is operatively connected with the shaft 3 under certain conditions, as will hereinafter more fully appear.

30 A lever 26 is fulcrumed to the standard for sliding the sleeve 6 into engagement with the gear wheel 4, against the tension of the spring 18, the lever 26 having a fork 27 straddling a ring 28 mounted loosely upon the sleeve 6 between the hub of the gear wheel 25 and a collar 29 secured upon the sleeve 6. The ring 28 has trunnions 30 engaged by the arms of the fork 27 whereby when the lever 26 is swung, it will slide 40 the sleeve 6 along the shaft 3 without interfering with the rotation of the sleeve 6.

The means for operatively connecting the gear wheel 25 and the gear wheel 4 secured upon the shaft 3, embodies a movably mounted counter shaft 31 journaled for rotation through a movable bearing 32 containing roller or other anti-frictional bearing elements and disposed loosely within an opening or recess 33 provided in the standard 16. The flexible element 24 passes over the bearing 32 and shaft 31. A gear wheel 34 is secured upon one end of the counter shaft 31 to intermesh with the gear wheel 4, the teeth of the gear wheels 4 and 34 being relatively short, and a gear wheel or pinion 35 is secured upon the other end of the counter shaft 31 and is provided with relatively long teeth intermeshing with the teeth 25^a of the internal gear wheel 25. Thus, the gear wheels 25 and 35 will stay in mesh while the gear wheels 34 and 4 are brought into and out of mesh.

The bearing or boxing 32 is movable within the opening 33 to and from the shaft 3 and sleeve 6, and is provided with side plates

36 overlapping the sides of the standard 16 to properly guide the bearing 32. The bearing 32 is provided at that end nearest the sleeve 6 with an angularly extending lug 37 adapted to be received by a notch 38 extending from the opening 33 at the respective end of said opening, whereby the bearing 32 is held in position with the gear wheel 34 in mesh with the gear wheel 4. The corners of the bearing or boxing 32 which work 75 along the edge of the opening 33 are provided with suitable roller bearings 39, whereby the bearing 32 will move easily when necessary.

In order to yieldably hold the lug 37 within the notch 38, and to move the bearing 32 away from the sleeve 6 when the lug 37 is released, an oblique yoke 40 is terminally attached to the side plates 36 of the bearing 32, and the intermediate portion of the yoke 85 40 is slidable upon an oblique stem 41 carried by the standard 16 and projecting away from the sleeve 6, a coiled wire expansion spring 42 being disposed upon the stem 41 between the yoke 40 and a nut or adjusting member 43 threaded upon the stem 41. The spring 42 tends to move the bearing 32 to one side to engage the lug 37 in the notch 38, and also tends to move said bearing away from the notch 38, for the reasons indicated.

In operation, supposing the spring 19 to be wound up, as illustrated in the drawings, the bearing 32 will be released and will be moved away from the sleeve 6, for reasons 100 which will hereinafter appear, and this will carry the counter shaft 31 with the bearing 32 to disengage the gear wheel 34 from the gear wheel 4. The sleeve 6 engaging the non-rotatable sleeve 10 will prevent the 105 sleeve 6 from rotating under the influence of the main spring 19, so that the main spring will not unwind prematurely. Now, to rotate the shaft 3 for starting the engine, the lever 26 is operated by the hand or in any other suitable manner, to move the sleeve 6 away from the sleeve 10, as seen in Fig. 2, and into engagement with the clutch hub 5 of the gear wheel 4. This will release the sleeve 6 so that the spring 19 can 115 unwind, and the shaft 3 will be rotated with the sleeve 6 to turn over the cranks of the engine for starting it. The lever 26 is immediately released as soon as the spring 19 is brought into play, which will disengage 120 the sleeve 6 from the shaft 3, or the gear wheel 4 thereof, and will again bring the sleeve 6 into engagement with the sleeve 10. The spring 19 in unwinding will separate the arms 21 and thereby pull the flexible element 24 toward a straight line position, which results in said element forcing the bearing or boxing 32 toward the sleeve 6 against the tension of the spring 42. The lug 37 will then snap into the notch 38 under 130

the influence of the spring 42, and this will hold the bearing 32 in position with the gear wheel 34 in mesh with the gear wheel 4. The engine having been started will cause 5 the gear wheel 34 to be rotated with the gear wheel 4, so that the gear wheel 25 will be rotated by the shaft 31, and this will cause the sleeve 6 to be rotated in a direction opposite to the rotation of the shaft 3 10 for winding the main spring 19. When the spring 19 is wound up, the tension thereof will cause the gear wheel 4 to thrust the gear wheel 34 to one side, so that the bearing 32 is moved away from the notch 38, to disengage 15 the lug 37 from said notch, and the spring 42 will then immediately move the bearing 32 away from the sleeve 6, as seen in Fig. 3, to disengage the gear wheel 34 from the gear wheel 4. The spring 19 is thus dis- 20 connected from the shaft 3 after the spring is wound up, and the sleeve 6 being held by the sleeve 10 will prevent the spring 19 from unwinding. The spring 19 is thus wound up for again starting the engine at a sub- 25 sequent time, the power being stored in the spring 19 for this purpose.

The present mechanism is entirely automatic in operation and requires no manual attention for winding up the main spring, 30 it only being necessary for the operator to operate the lever or actuating member 26 when it is desired to start the engine. The gear wheel or pinion 35 being of much smaller diameter than the gear wheel 25 35 will provide a gear ratio whereby the spring 19 can be slowly wound up by the shaft 3 without the liability of retarding or arresting the motion of the engine.

Having thus described the invention, what 40 is claimed as new is:

1. In a mechanism of the character described, a shaft, a sleeve thereon, a spring connected to said sleeve, means for sliding the sleeve upon the shaft, means for preventing the rotation of the sleeve when it is moved in one direction, means for connecting the sleeve to the shaft when it is slid in the other direction, an internal gear wheel secured to the sleeve, a counter shaft, a 45 pinion secured to the counter shaft and meshing with the internal gear wheel, a pair of gear wheels secured to said shafts and adapted to be brought into and out of mesh, and means for automatically bringing said pair of gear wheels into and out of mesh when said spring is unwound and wound up, respectively.

2. In a mechanism of the character described, a shaft, a sleeve thereon, a spring 60 connected to the sleeve, means for sliding the sleeve, means for preventing the rotation of the sleeve when it is slid in one direction, and means for connecting the sleeve to the shaft when it is slid in the other direction, an internal gear wheel secured to the sleeve, 65

a movably mounted counter shaft, a pinion carried by the counter shaft and meshing at all times with the internal gear wheel, a pair of gear wheels secured to said shafts and adapted to be brought into and out of mesh, means for moving said counter shaft toward the first mentioned shaft when the spring is unwound, and means for holding said counter shaft when it is moved toward the first mentioned shaft and for moving 70 it away from the first mentioned shaft when the spring is wound up.

3. In a mechanism of the character described, a shaft, a sleeve thereon, a spring connected to the sleeve, means for sliding 80 the sleeve, means for preventing the rotation of the sleeve when it is slid in one direction, means for connecting the sleeve with the shaft when the sleeve is slid in the other direction, a movably mounted counter shaft, gears continually connecting said counter shaft and sleeve, a second set of gears for connecting said shafts, and means for mounting said counter shaft whereby when the spring is unwound and wound up it will 85 bring the second set of gears into and out of mesh, respectively.

4. In a mechanism of the character described, a shaft, a sleeve thereon, a spring connected to the sleeve, means for sliding 95 the sleeve, means for preventing the rotation of the sleeve when it is slid in one direction, means for connecting the sleeve with the shaft when it is slid in the other direction, a movable bearing, a supporting member for said bearing, a counter shaft journaled through said bearing, gears continually connecting said counter shaft and sleeve, a second set of gears for connecting said shafts, said bearing and supporting member having interengageable means for holding the second set of gears in mesh and arranged to be disengaged when the spring is wound up, means for moving the bearing toward the first mentioned shaft when the spring is unwound, and spring means for holding the bearing in engagement with the supporting member and for moving the bearing away from the sleeve when the bearing is released, to disengage the second set of gears and to allow said second set of gears to come into mesh when the spring is 100 unwound.

5. In a mechanism of the character described, a shaft, a sleeve thereon, a spring connected to the sleeve, means for sliding the sleeve, means for preventing the rotation of the sleeve when it is slid in one direction, means for connecting the sleeve with the shaft when it is slid in the other direction, an internal gear wheel secured to the sleeve, a movable bearing, a supporting member for said bearing having an opening and a notch, the bearing being disposed in said opening and having a lug engageable 110 115 120 125 130

in said notch when the bearing is moved toward the sleeve, a counter shaft journaled through said bearing, a pinion carried by the counter shaft and continually meshing with said internal gear wheel, a pair of gear wheels secured to said shafts and adapted to be brought into and out of mesh when the bearing is moved toward and away from the sleeve, respectively, means for moving the bearing toward the first mentioned shaft when the spring is unwound, and spring means connected to said bearing for holding said lug in said notch and for moving

the bearing away from said sleeve when the spring is wound up, said lug being disengaged from said notch when the spring is wound up, and the bearing being moved toward the sleeve when the spring is unwound to engage said lug in said notch. 15

In testimony that I claim the foregoing 20 as my own, I have hereto affixed my signature in the presence of two witnesses.

JOHN WESLEY BECK.
